RECEPTACLE FOR TOYS

Emil Strand, St. Louis, Mo.

Application February 14, 1949, Serial No. 845

Term of patent 3½ years

(Cl. D34—15)

To all whom it may concern:

Be it known that I, Emil Strand, a citizen of the United States, residing in the city of St. Louis and State of Missouri, have invented a new, original, and ornamental Design for a Receptacle for Toys, of which the following is a specification, reference being had to the accompanying drawing, forming part thereof.

In the drawing,

Fig. 1 is a plan view of a receptacle for toys incorporating my new and ornamental design,

Fig. 2 is an elevational view of one end of said receptacle,

Fig. 3 is an elevational view of one side of said receptacle (the other side of said receptacle being identical), and

Fig. 4 is an elevational view of the other end of said receptacle.

I claim:

The ornamental design for a receptacle for toys, substantially as shown and described.

EMIL STRAND.
